UNITED STATES PATENT OFFICE.

WILLIAM GRAY, OF TORONTO, ONTARIO, CANADA.

FURNACE.

SPECIFICATION forming part of Letters Patent No. 233,614, dated October 26, 1880.

Application filed May 6, 1880. (No model.) Patented in Canada April 3, 1880.

To all whom it may concern:

Be it known that I, WILLIAM GRAY, of the city of Toronto, in the county of York, in the Province of Ontario, Canada, engineer, have 5 invented certain new and useful Improvements in Furnaces, of which the following is a specification.

My invention has relation more particularly to a smoke-consuming attachment which is applicable to boiler and other furnaces, and, as the name indicates, is designed to prevent the passage of smoke from the furnace by causing it to be consumed therein.

In the operation of my invention I prefer to 15 combine the attachment with the door of the furnace, but do not confine myself to its use in any particular position on the furnace.

Referring to the accompanying drawings, Figures 1 and 2 are sections of the front of a 20 furnace to which my invention is shown as applied. Fig. 3 is a front view of the same.

A are the furnace-walls; B, the grate-bars; C, the door, and C', the metallic front or frame supporting the door.

25 D is a regulating-damper, hinged at the top to upper part of the door and inclosed at the ends by wings d d, which form a part of the door. In front of this damper, on the furnace side, is placed a deflecting-plate, E, against the lower 30 edge of which the damper bears when closed, but which from this point of contact upward inclines inwardly toward the furnace and away from the damper. The vertical sides of this plate are connected to the door; but an opening is provided at the top for the passage of air when the damper D is opened. The damper is provided with a pivoted pawl, D', which acts in connection with ratchet-teeth formed on the deflecting-plate in such manner that the 35 damper can be opened by the movement of the

pawl-handle and held at any desired position by the force of its own weight.

When the regulating-damper is opened, as shown in Fig. 2, an air-passage is formed into the furnace, through which passage the air 45 rushes, as shown by arrows, into the upper portion of the fire-chamber and supplies the oxygen necessary to consume the smoke, which, as is well understood, is unconsumed carbon, carried upward and usually out of the furnace 50 in the form of smoke for the want of sufficient oxygen properly applied to consume it.

It is obvious that my attachment can be applied to a furnace independently of the door; but it is equally obvious that combined with 55 the door the arrangement is more convenient, simple, and economical.

The advantages of my invention are that the escape and nuisance of smoke are prevented, and the smoke being entirely consumed I gain 60 an economy of fuel.

I claim as my invention—

1. The combination, with a furnace-door provided with the deflecting-plate E, extending from the bottom of the door upwardly and at 65 an inclination toward the furnace, and having side wings, d d, of the hinged regulating-damper D, said deflecting-plate, wings, and damper forming a passage for the admission of air to the upper part of the furnace, substantially as 70 and for the purpose set forth.

2. The combination, with the deflecting-plate E, provided with ratchet-teeth, side wings, d d, and the hinged damper D, of the pivoted lever and pawl D', substantially as 75 shown and described.

W. GRAY.
